UNITED STATES PATENT OFFICE

JOODEFRIDUS HENDRIKUS CLERKX VAN KEULEN, OF THE HAGUE, NETHERLANDS, AS
SIGNOR TO NAAMLOOZE VENNOOTSCHAP DE BATAAFSCHE PETROLEUM MAAT-
SCHAPPIJ, OF THE HAGUE, NETHERLANDS, A COMPANY OF THE NETHERLANDS

BLOW-OUT PREVENTER

Application filed March 18, 1929, Serial No. 347,999, and in the Netherlands December 29, 1928.

My invention relates to improvements in blow out preventers as used for checking the flow of oil, gas, etc. from deep wells. As the casing often contains a string of drill pipe, drilling rods, or a cable, the casing head should also be adapted to seal the annular space around said members. Present blow out preventers have, inter alia, the inconvenience that it is difficult to apply the required checking members when the explosion or eruption has already begun, or to satisfactorily seal the drilling rod or cable. Moreover, when the head comprises a slide valve member, the difficulty is experienced that the tightness of the shut off is not increased by the pressure acting from below. Still another disadvantage of present devices of this character is that the drilling rod cannot well be clamped if, as often occurs, its thickness is somewhat reduced.

The object of the present invention is to void the aforesaid inconveniences and to provide for a well a blow out preventer which is reliable in operation under all conditions. With this object in view, my invention consists in the combination of certain parts as defined in the appended claims.

In order that the invention may be clearly understood, I shall now proceed to describe the same in detail with reference to the annexed drawings, illustrating a preferred embodiment thereof by way of example but not of limitation, and in which

Fig. 1 is partly a top view, partly a horizontal section on the broken line I—I in Fig. 2.

Fig. 2 is partly a side elevational view of the interior of the blow out preventer, partly a vertical section on the broken line II—II in Fig. 1.

Figs. 3-7 are diagrams illustrating five characteristic positions of the checking and sealing members.

The housing 2, which is adapted to be secured to the top of the deep well casing by means of a bottom flange 1, is provided with ear and front covers 3 and 4, respectively, and encloses two rollers 5, 6 which snugly fit the curved inner walls of the housing and are in contact with one another along a generatrix. Said rollers are symmetric as far as the

recesses therein are concerned. As to these recesses the portions 7 thereof are cylindrical and have a radius equal to that of the passages of the bottom flange 1 and the top flange 10, whereas the portions 8, which are also cylindrical and the axes of which are at right angles to those of the portions 7, have a diameter slightly smaller than the minimum thickness of the drill stem to be used. That portion of each recess, which forms the transition between the cylindrical portions 8 and 7, is flared and so shaped that in planes passing through the axis of the roller its profile is as far as possible circular, it being understood that at 9 the cross sectional area of the passage constituted by said flared portions of both rollers slightly exceeds that of the maximum thickness of the drilling rod used.

The rollers 5, 6 are provided on their end faces with square sockets 11 for receiving square blocks 12 each having a square hole into which projects a square of a worm shaft 13. Each worm shaft 13 carries a worm wheel 14 cooperating with a worm 15, the spindle 18 of which passes through a stuffing box 17.

The worm wheels 14 and, consequently, the rollers 5, 6 are adapted to be rotated in opposite directions because of the one worm having a right handed and the other a left handed thread.

In the space below the rollers 5, 6 the full pressure of the explosion or eruption may set up. This necessitates the provision of the stuffing box 17 for avoiding the escape of gases and liquid leaking along the worm wheel shafts 13, and of nozzles 16 for the connection of discharge pipes.

When the rollers 5 and 6, by means of the worm mechanism, have been turned into the position shown in Fig. 3, the drilling rod can 90 freely be lowered into the well casing. After the introduction of said stem, the rollers are turned until they assume the position shown in Fig. 4. In this position, the cross sectional area of the passage at 9 is sufficient to 95 ensure the required lateral freedom of motion of the drilling rod 19. In the case of an eruption, all that is required is turning the rollers a little further into the position illustrated in Fig. 5, when the drilling rod 100

19 is firmly clamped and thereby secured against upward motion under the pressure of the oil and gases, whereas the point around said stem is tightly sealed so that no oil or gas can escape.

The worm spindle 18 should be of such a length that the shut-off mechanism can be operated from a safe distance.

Fig. 6 shows how the rollers 5, 6 completely shut off the mouth of the well if no drilling rod projects from the same.

The housing 2 still contains wedge-shaped keys 20 and bearing bars 21 snugly fitting against the covers 3, 4 and the rollers 5, 6. If said keys are tightened up, the rollers, which move slightly apart when clamping the drill stem, will again be forced against one another whereby a perfect seal is ensured. When the keys 20 have been tightened, the worm wheels can no more be turned so that no accidents can occur.

As will be seen, the blocks 12 have a small amount of clearance in their sockets 11, so that the forces which tend to move the rollers apart cannot be transmitted to and cause dangerous stresses in the operating mechanism.

The rollers being provided with sockets 11 at both ends, they can be placed rightside left.

In the position shown, the walls of the recesses 8, 9 act to prevent the drilling rod from being forced upward. If, however, the rollers are placed rightside left, they can be used to prevent the rod from falling into the well, both during the introduction of the rod into and its removal from the well. For this and other purposes it may be desirable to provide the rollers with intermeshing spur wheels instead of worm wheels and to secure to one of the roller shafts a lever by means of which the opening and the shutting-off can be effected very quickly.

The roller shafts may project from the housing 2 and be provided with disks indicating the position assumed by the recesses in the rollers.

After removal of the rear cover 3, the rollers can easily be withdrawn from their housing and be placed rightside left, or be replaced by other rollers if a drilling rod of a different gauge is to be used.

The recesses of the rollers may be so formed as to be adapted to clamp, instead of a circular or square drilling rod of a given gauge, a rope or similar flexible element.

What I claim is:—

1. In a blow-out preventer for wells and the like, a housing having aligned top and bottom flanges, two rotatable rollers horizontally mounted in said housing so as to engage one another along a generatrix, and means for rotating said rollers in opposite directions, said rollers having symmetrical mating recesses adapted to form a passage the axis of which coincides with the common

axis of said flanges, the recess of each roller comprising, in addition to a semi-cylindrical portion having a radius equal to that of said flanges, a semi-cylindrical portion having smaller radius, the generatrices of both said portions extending at right angles to the axes of said rollers but being angularly disposed relative to one another, the recess having a smaller radius comprising a flared portion forming a transition into the recess having the larger radius.

2. In the combination, as specified in claim 1, bearing bars provided in said housing snugly fitting against the covers thereof a wedge-shaped keys in contact with said bearing bars and arranged to forcibly move said rollers into contact with one another, at the same time locking the means for rotating said rollers.

In testimony whereof I affix my signature:

GODEFRIDUS HENDRIKUS CLERKX van KEULEN
